(57) **CLAIM**

The ornamental design for a water addition plug for storage battery as shown and described.

DESCRIPTION

FIG. 1 is a perspective view of a first embodiment of our new design;

FIG. 2 is another perspective view of the first embodiment thereof;

FIG. 3 is a front view of the first embodiment thereof;

FIG. 4 is a rear view of the first embodiment thereof;

FIG. 5 is a top view of the first embodiment thereof;

FIG. 6 is a bottom view of the first embodiment thereof;

FIG. 7 is a right-side view of the first embodiment thereof;

FIG. 8 is a left-side view of the first embodiment thereof;

FIG. 9 is a cross-sectional view taken along lines 9-9 in FIG. 3;

FIG. 10 is a cross-sectional view taken along lines 10-10 in FIG. 5;

FIG. 11 is a perspective view of a second embodiment of our new design;

FIG. 12 is another perspective view of the second embodiment thereof;

FIG. 13 is a front view of the second embodiment thereof;

FIG. 14 is a rear view of the second embodiment thereof;

FIG. 15 is a top view of the second embodiment thereof;

FIG. 16 is a bottom view of the second embodiment thereof;

FIG. 17 is a right-side view of the second embodiment thereof;

FIG. 18 is a left-side view of the second embodiment thereof;

(Continued)

FIG. 19 is a cross-sectional view taken along lines 19-19 in FIG. 13;
FIG. 20 is a cross-sectional view taken along lines 20-20 in FIG. 15;
FIG. 21 is a perspective view of a third embodiment of our new design;
FIG. 22 is another perspective view of the third embodiment thereof;
FIG. 23 is a front view of the third embodiment thereof;
FIG. 24 is a rear view of the third embodiment thereof;
FIG. 25 is a top view of the third embodiment thereof;
FIG. 26 is a bottom view of the third embodiment thereof;
FIG. 27 is a right-side view of the third embodiment thereof;
FIG. 28 is a left-side view of the third embodiment thereof;
FIG. 29 is a cross-sectional view taken along lines 29-29 in FIG. 23;
FIG. 30 is a cross-sectional view taken along lines 30-30 in FIG. 25;
FIG. 31 is a perspective view of a fourth embodiment of our new design;
FIG. 32 is another perspective view of the fourth embodiment thereof;
FIG. 33 is a front view of the fourth embodiment thereof;
FIG. 34 is a rear view of the fourth embodiment thereof;
FIG. 35 is a top view of the fourth embodiment thereof;
FIG. 36 is a bottom view of the fourth embodiment thereof;
FIG. 37 is a right-side view of the fourth embodiment thereof;
FIG. 38 is a left-side view of the fourth embodiment thereof;

FIG. 39 is a cross-sectional view taken along lines 39-39 in FIG. 33; and,
FIG. 40 is a cross-sectional view taken along lines 40-40 in FIG. 35.
